UNITED STATES PATENT OFFICE.

LOUIS CASPER, OF CHICAGO, ILLINOIS, ASSIGNOR TO HYGEIA VIBRATORY COMPANY, A CORPORATION OF MAINE.

MASSAGE INSTRUMENT.

SPECIFICATION forming part of Letters Patent No. 742,287, dated October 27, 1903.

Application filed June 4, 1901. Serial No. 63,051. (No model.)

To all whom it may concern:

Be it known that I, LOUIS CASPER, of Chicago, Illinois, have invented certain new and useful Improvements in Massage Instruments, of which the following is a specification.

The present invention relates to a massage instrument in which there is a device for producing a tapping or kneading effect and means for cushioning the blows from said tapping device, so that the blows do not fall directly on the body of a patient, but are intercepted by a medium which is further utilized to transmit the blows to one or more points on the body. The means which I employ are illustrated in the accompanying drawings, and the details and novel features of the invention will hereinafter be fully described.

In the drawings, Figure 1 is a perspective view of a belt embodying features of my invention. Fig. 2 is a top or edge view of the belt. Fig. 3 is an enlarged horizontal and central section of the belt and of a case containing the tapping device. Fig. 4 is a view of a portion of the belt, showing one of the parts for producing a kneading or vibrating action on the skin or tissues of the body. Fig. 5 is a cross-section of same, taken on line 5 5 of Fig. 4. Fig. 6 is a sectional elevation of a small hand instrument in which my invention is embodied for the purpose of operating on a single portion of the body at one time. Fig. 7 is a side elevation of an instrument, showing a modification. Fig. 8 is a sectional view of a hand instrument for operating on several points at once within a small area. Fig. 9 is a face view of the operating cushion or plate shown in Fig. 8, and Fig. 10 is a sectional view of a belt having a pendent or supplementary loop provided with vibratory parts.

Heretofore in appliances having mechanical means for producing a massage or vibratory action on the human body the striking or tapping devices have usually acted in each case by the hammer or tapper striking directly on the surface of the skin.

In carrying out my invention I employ means for cushioning the hammer, the cush-

ion being placed between the hammer and the part or parts to be operated on. This has the effect of making a softened blow or kneading-like action on the skin and body tissues much similar to that produced by the tip of the human finger. The cushion I employ can be of various shapes or constructions, according to the use desired. I have illustrated in the drawings my invention as applicable for massage purposes to various parts of the body, a particular form of the invention being in having the cushion in the form of a belt or tube, which enables a vibratory action to be imparted to several parts of the body simultaneously, and, if desired, an electrical action may also be imparted at the same time, the two actions being beneficial in the treatment of all diseases affecting the organs of the abdominal region. The following is a description of the massage instrument as made in the form of a belt, Figs. 1 to 5 being more particularly referred to:

A refers as a whole to a cushion which is preferably hollow or tubular for holding a fluid which acts as a medium communicating with vibratory parts at various points of the cushion. As shown in the drawings, the cushion when shaped for a belt is made of a tube *a*, of rubber or other suitable material, and is provided at its ends with a buckle *a'* and a flap *a''* to fasten the belt around the body.

b designates slots arranged around inside of the belt and covered with thin diaphragms *b'*, of rubber, each of which is secured to the tube *a* by a circular reinforcement *b''*. At the front of the tube is a slot *c*, having a diaphragm or vibratory part *b³*, which may have a central knot or projection *b⁴* to receive the impacts from the hammer of the tapping device. A valve *d* is employed for filling the tube with a fluid, preferably water, as indicated at *w*.

E refers as a whole to a tapping device, which is preferably constructed as follows:

E' is a case containing an electromagnet *e* and a vibratory armature *e'*. Projecting from the armature is a rod or arm *e''*, which extends outside of the case and has on its outer end a head or hammer *e³*. This is arranged so that in action it will strike the vibratory part *b³* on the extreme end of tube.

e^4 is a spring for keeping the armature out of contact with pole-pieces of the magnets, (one only being shown in drawings.)

Below the armature e' is a plate e^4 , having 5 a contact-piece e^5 . A small tongue e^6 on the armature normally makes contact with the piece e^5 . Wires x x' connect the coils of the magnets e and the plate e^4 with a battery Y . e^7 is a push-button for closing circuit connections.

L L' are electrodes attached to movable loops on the belt a , and z z' are connections or wires to a suitable source of electricity. It is not absolutely necessary that electrical 15 action should be supplied in connection with the massage action of the instrument; but I preferably combine them, as the two actions in an instrument have advantages in many instances.

20 The operation of the instrument just described is as follows: The belt having been buckled around the waist and the circuit operating the tapping device closed, the hammer will strike the exterior vibratory part or 25 belt. This imparts an impulse to the fluid in the tube which communicates with the several vibratory parts or diaphragms next to the body of the patient, causing the said parts to vibrate and impart a kneading action to 30 the skin and tissues beneath same. By employing electromagnetic mechanism to operate the tapping or striking device vibrations or movements of a high rate of speed may be readily obtained and are beneficial in the 35 therapeutic applications of the instrument.

It will be observed that the instrument may be modified without departing from the spirit of the invention. In Fig. 6 I have shown a small hand instrument in which the cushion 40 consists of a ball a^{10} . In Fig. 7 the cushion consists of a pencil a^{20} , of soft rubber, which may be used for massaging the aural passages. In Fig. 8 the cushion is a hollow disk a^{30} , having protuberances a^{31} , which act on 45 the skin, and in Fig. 10 I have shown a belt having a supplementary loop or tube a^{40} , having vibratory parts on same.

Having thus described my invention, what I claim as new therein, and desire to secure 50 by Letters Patent, is—

1. An instrument of class described, having a striking or tapping device and a cushion which receives the blows from the hammer of the tapping device and is adapted to 55 impart same to the human body, as set forth.

2. An instrument of class described, having a striking or tapping device and a cushion

ion which is engaged by the hammer of the tapping device, the said cushion being provided with vibratory parts adapted to be placed against the human body, as set forth.

3. An instrument of class described, having a striking or tapping device and a cushion filled with a fluid medium, the said cushion being engaged by the hammer of the tapping device and adapted to impart the blows from same in the manner set forth.

4. An instrument of class described having a tapping device a hammer of which engages an exterior part of a tubular cushion, the said cushion being provided with vibratory parts adapted to be placed against the human body, as set forth.

5. In an instrument of class described, a cushion adapted to be placed against the human body and a vibratory hammer which strikes an exterior part of the cushion, as set forth.

6. A massage instrument having a cushion, a vibratory hammer which strikes an exterior part of same and electromagnetic mechanism for actuating the hammer, as set forth.

7. The combination of a tapping device having an electromagnet, a vibratory armature, a rod from same provided with a head or hammer, and a cushion having an exterior part which receives blows from said hammer, the cushion being adapted to impart the blows in the manner set forth.

8. A massage instrument comprising a tubular belt, slots provided with diaphragms adapted to be placed against the human body, a vibratory part on exterior of the belt and a striking or tapping device, as set forth.

9. A massage instrument having a tubular belt adapted to be placed against the human body and a tapping device which engages an exterior part of the belt, as set forth.

10. In a massage instrument the combination of a cushion comprising a fluid medium, adapted to be placed against the body, and means for vibrating said medium, substantially as set forth.

11. In a massage instrument the combination of a cushion comprising an elastic casting and a liquid medium therein, and means for vibrating said medium, substantially as set forth.

In testimony whereof I have hereunto set my hand this 31st day of May, 1901.

LOUIS CASPER.

In presence of—

W. W. MAIN,
Wm. ROCHE.
